ELECTRODE

Francis C. Ellis, Chicago, Ill.

Application August 21, 1937, Serial No. 160,283

2 Claims. (CL 173—324)

The present invention relates to an electrode for conveying a current flowing through or adjacent a given surface.

In many electrical processes it is necessary to apply an electrode to a surface for the purpose of passing an electric current between said surface and the electrode as, for example, when it is desired to measure or ascertain the properties of the said current.

10 In particular when employing devices, such as the electro-cardiograph or other electrical diagnostic device, it is necessary to make a contact between the surface of the body and an electrode in order to determine the characteristics of the existing electrical effect. As long as the pressure with which the electrode is applied to the surface is maintained constant, the current flowing between the electrode and the surface will remain uniform, other factors being constant. A variation, however, in the contact pressure may tend to affect the current flow by increasing or decreasing the resistance at the point of contact and it is accordingly necessary to exert special care to maintain a constant contact pressure on the electrode when the connection or the point of contact is varied, if it is desired to obtain constant results.

It is, therefore, a purpose of the present invention to provide an electrode which is constructed and arranged in a novel manner so that, when applied to a surface, the contact pressure therewith will always remain substantially constant even though the manual force of application is varied within wide limits.

35 Numerous other objects and advantages will more fully appear during the course and progress of the following specification.

Referring to the drawing:

Figure 1 is a perspective view of an electrode constructed in accordance with the present invention.

Figure 2 is a sectional elevation taken on the line 2—2 in Figure 1.

45 Figure 3 is an alternative form of an electrode constructed in accordance with the present invention.

Figure 4 is a sectional view taken on the line 4—4 in Figure 3.

The illustrative embodiment disclosed in Figure 1, comprises a cylindrical handle portion 10 of suitable insulating material, such as Bakelite, which is provided interiorly and axially thereof with a tubular insert 12 which may comprise any other suitable tube, preferably of metal.

55 About the lower end of the handle portion, as

viewed in Figure 1, is secured a sleeve 14 also of insulating material which is rigidly secured to the handle portion in any desired manner. The lower edge of the sleeve 14 is provided with an inwardly extending annular lip 16 for a purpose 5 which will hereinafter be described more in detail.

The electrode proper or conducting member 18 is of cylindrical shape and has secured about the upper end thereof a cylindrical sleeve 20 10 which engages into the inner cylindrical bore of the sleeve 14 and provides a bearing surface therewith of considerable extent so that the contact member 18 may be reciprocated axially of the handle and sleeve but will always be maintained in position extending longitudinally of the axis of the sleeve. The shoulder 22 formed by the lower end of the sleeve 20, moreover, engages with the inner side of the annular, inwardly extending lip 16, providing a stop for limiting movement of the conducting member 18 with respect to the sleeve, while a compression spring 24 20 serves to maintain the electrode normally in said limiting position.

Further means is provided to guide and position the conducting member 18 and comprises a cylindrical rod 26 of some suitable conducting material of the proper diameter to engage slidably within the tubular insert 12. Electrical contact with the conducting member 18 is made 30 through the agency of a standard cord tip connector 28 threaded into the upper end of the handle, as viewed in Figure 1, and having soldered to the lower portion thereof a flexible wire 30. This wire extends loosely through the interior 35 space formed by the tubular insert 12 and connects with the cylindrical rod 26 through the agency of a set screw 32.

In use, the electrode is connected with the electrical device in conjunction with which it is 40 intended to be employed through the agency of any suitable electrical conduit having its end inserted into and making contact with the cord tip connector 28. The handle portion 10 may then be grasped manually and the conducting 45 member 18 presented flatwise against the surface to be measured with sufficient force so that the annular lip portion 16 of the sleeve is brought against the surface. Regardless of how much additional force is applied through the handle 50 10, the electrode cannot be moved forwardly any further into contact with the surface since movement is limited by the said annular lip 16.

Meanwhile, however, the conducting member 18 will have been forced into the sleeve against the

- resilient action of the spring 24 until its outer surface is substantially in the same plane with the end of the sleeve 14 in which position the compression spring 24 will always exert a constant pressure thereagainst. If it is desired to break the contact with the surface and again remake it at some later time or at some different position, the conducting member 18 will always be retracted to the same relative position when the electrode is firmly pressed against the surface in the manner hereinbefore mentioned, with the result that the contact pressure, during each time of use, will remain substantially the same. As a result, the electrical current flowing through the circuit comprising the surface to be measured, the conducting member 18, the conducting rod 26 and the wire 30, the cord tip connector 28 and the conduit connected thereto will be unaffected by differences in contact pressure.
- 20 According to the alternative preferred embodiment disclosed in Figures 3 and 4, the sleeve 14 is considerably flared at the bottom edge thereof as at 34 to provide a lower contact surface 36 of considerable area. This form of construction is preferred when employing the electrode against surfaces which are relatively soft and in which the edge of the sleeve 14 may tend to sink if of only inconsiderable extent. Thus, in applying the outer face of the conducting member 18 to the surface of the body, the device is always accurately positioned by the surface 36 so that the area contacted by the surfaces of the conducting member 18 will be contacted with the same force at all times.
- 35 The conducting member 18 shown in Figures 3 and 4, is provided with an annular shoulder 38 which, in conjunction with the annular lip 16, limits the outward movement thereof. According to this embodiment there is provided a plurality of spaced conducting members since the electrode proper, as indicated by the numeral 18, is split into a right and left section, 40 and 42, respectively, as viewed in Figure 3. These two sections are separated and electrically insulated from one another by the interposed layer of non-conducting material 44.
- 40 The structure is preferably generally cylindrical in shape and the two conducting portions 40 and 42 and the insulating barrier 44 may be cemented together or formed into a unitary unit by any suitable means. As in the previously described embodiment, the conducting rod 26 extends into the tubular insert 12 to position the conducting member for slidable movement with respect to the handle. A double cord tip connector 46 is mounted on the end of the electrode and has conducting portions 48 adapted to make electrical contact with the cord tips on the conduits of the instrument with which the present invention is to be employed. Flexible insulated wires 50 connected at their upper ends respectively to the

cord tip connector extend interiorly of the device through the tubular insert 12 and are secured to the respective conducting portions 40 and 42 of the conducting rod 26 by means of set screws 32.

5 This embodiment is of particular utility where it is desired to contact a surface with spaced electrodes, in view of the fact that the two conducting portions 40 and 42 are spaced by the intermediate partition 44 and are completely insulated 10 one from the other. The conducting portion may be of any suitable metal such as zinc or copper, for example, and if desired may comprise in the same unit dissimilar metals, in the event it is desired to measure an electrolytic effect.

15 It is thought that the invention and numerous of its attendant advantages will be understood from the foregoing description and it is obvious that numerous changes may be made in the form, construction and arrangement of the several parts 20 without departing from the spirit or scope of the invention, or sacrificing any of its attendant advantages, the form herein described being a preferred embodiment for the purpose of illustrating the invention.

25 The invention is hereby claimed as follows:

1. In a contacting device for making electrical contact with a surface of a body or the like comprising an electrode support having a manual control handle for facilitating application to said surface, said contacting device comprising a relatively rigid, gauging surface arranged in a predetermined relatively flat plane, an electrode arranged generally centrally of said surface and having a conducting contact surface associated therewith, said electrode being movable to positions laterally on either side of said plane, and resilient means for applying a constant force to said conducting surface when the two surfaces are substantially co-planar, said conducting contact surface comprising two separate sections of dissimilar materials and having an insulating partition therebetween.
